US00D530593S

(12) **United States Design Patent** (10) **Patent No.:** **US D530,593 S**
Kosasih et al. (45) **Date of Patent:** **** Oct. 24, 2006**

(54) **KNOB**

(75) Inventors: **Angie L. Kosasih**, Rancho Santa Margarita, CA (US); **Amy Liu**, Monterey Park, CA (US); **Aaron E. Hanna**, Corona, CA (US)

(73) Assignee: **Newfrey LLC**, Newark, DE (US)

(**) Term: **14 Years**

(21) Appl. No.: **29/213,376**

(22) Filed: **Sep. 16, 2004**

(51) LOC (8) Cl. **08-06**

(52) U.S. Cl. **D8/310**

(58) **Field of Classification Search** **D8/301, D8/302, 307, 310, 338, 350, DIG. 2, 352, D8/379; 16/86 A; 70/107; 292/347, 356, 292/357; 428/583; D23/250, 251, 254**

See application file for complete search history.

(57) **CLAIM**

The ornamental design for a knob, as shown and described.

DESCRIPTION

FIG. 1 is a perspective view of a knob showing my new design;

FIG. 2 is a front elevational view thereof;

FIG. 3 is a top plan view thereof, the bottom view being a mirror image;

FIG. 4 is a right side elevational view thereof, the left side is a mirror image; and,

FIG. 5 is a rear view thereof.

The broken lines in the Figures are for illustrative purposes only and form no part of the claimed design.
